UNITED STATES PATENT OFFICE.

LOUIS W. LEVY, OF NEW BRIGHTON, NEW YORK.

DESIGN FOR A HOLDER FOR TOILET OR SIMILAR ARTICLES.

SPECIFICATION forming part of Design No. 35,200, dated October 22, 1901.

Application filed May 2, 1901. Serial No. 58,551. Term of patent 7 years.

To all whom it may concern:

Be it known that I, LOUIS W. LEVY, a citizen of the United States, residing in New Brighton, Richmond county, city and State of New York, have invented and produced a certain new and original Design for a Holder for Toilet or Similar Articles, of which the following is a specification.

This design relates to a holder for toilet articles and the like, and provides a new shape for such an article.

● The new design is shown in the accompanying drawing, which is a perspective view of a holder embodying my new design.

15 Referring to the drawing, A represents as a whole the portion intermediate between the ends and between the portions B and C, hereinafter referred to, and is approximately of elongated cylindrical form.

20 B represents as a whole a portion of bulbous shape, which is at one end of the portion A and which is of greater diameter than the portion A and of considerable length axially.

C represents as a whole a portion at the opposite end of the portion A, which is of greater diameter than the portion A and is approximately tapering, being smaller at its outer end.

25 D represents as a whole a relatively small approximately cylindrical protuberance which is at the outer end of the portion B. These principal portions A, B, C, and D of the holder are each ornamented in detail in the manner hereinafter described.

30 The portion A is ornamented by a single and encircling band *a*, which consists of a central roughened strip, as shown, flanked on opposite sides by parallel depressions. The band *a* is near the longitudinal center of the portion A. At the meeting-point of the portions A and B there is an enlarged band

or ring *b*, which, as shown, consists of a central convex band or ring flanked on each side by a smooth concave ring parallel therewith. At the meeting-point of the portions A and 45 C there is another enlarged band or ring *d*, consisting of a roughened convex strip flanked by a smooth convex strip parallel thereto. The portion D forms a distinctive feature of my design. It has an abrupt and approximately smooth and flat outer end *e*. It is conspicuous as a substantially cylindrical protuberance of reduced size as compared with the bulbous portion B and radically different therefrom in shape, size, and appearance. Approximate to the point at which the end wall *f* of the portion B joins the portion D there is a narrow rough band *g*, which encircles the portion D and which is bordered on each side by smooth convex ring-like strips 50 *h*. A slender smooth concave band *i* surrounds the portion D near its outer extremity. Intermediate the bands *g* and *i* the portion D is smooth and cylindrical, as shown at *j*. A slender projecting border *k* is provided 55 around the edge of the outer end *e*.

The several portions of the holder according to my design are in axial alinement.

The new design is of distinct and pleasing appearance, and the holder embodying it is 70 symmetrical and attractive in shape.

What I claim is—

The design for a holder for toilet or similar articles substantially as herein shown and described.

In witness whereof I have hereunto signed my name in the presence of two subscribing witnesses.

LOUIS W. LEVY.
